No. 717,946.

PATENTED JAN. 6, 1903.

E. E. THOMAS.

GANG SAW.

APPLICATION FILED MAR. 31, 1902.

NO MODEL.

UNITED STATES PATENT OFFICE.

EDWIN E. THOMAS, OF ST. PAUL, MINNESOTA, ASSIGNOR OF ONE-HALF TO UNION IRON WORKS, OF MINNEAPOLIS, MINNESOTA, A CORPORATION OF MINNESOTA.

GANG-SAW.

SPECIFICATION forming part of Letters Patent No. 717,946, dated January 6, 1903.

Application filed May 31, 1902. Serial No. 109,628. (No model.)

To all whom it may concern:

Be it known that I, EDWIN E. THOMAS, of St. Paul, Ramsey county, Minnesota, have invented certain new and useful Improvements 5 in Gang-Saws, of which the following is a specification.

The invention relates to sawmill machinery, and particularly to attachments for gang-saws. The saws employed in the machines of this 10 type are rigidly secured in a gate that is adapted to slide up and down in ways provided in the gang-frame. The saws are placed under great tension in their support, and the expansion of the sides of the gate, owing to its 15 rapid reciprocation in the ways, will sometimes cause breakage of the saws or other damage to the working parts of the machine.

The primary object, therefore, of my invention is to provide means in connection with 20 the reciprocating gate which will take up the expansion without affecting the gate or subjecting the saws to a greater strain than originally intended for them.

Other objects of the invention will appear 25 from the following detailed description.

The invention consists generally in a reciprocating saw-gate having suitable ways and bars interposed between said ways and gate and connected to the latter, said connections 30 permitting the expansion of said bars independently of the gate.

Further, the invention consists in various constructions and combinations, all as hereinafter described, and particularly pointed 35 out in the claims.

In the accompanying drawings, forming part of this specification, Figure 1 is a horizontal section of a gang-saw embodying my invention. Fig. 2 is a detail partially in section, showing the manner of supporting the saw-gate in the ways. Fig. 3 is a longitudinal section on the line *y* of Fig. 2.

In the drawings, 2 represents a suitable base of timbers whereon the gang-frame 3 is supported in the usual manner. Upon the frame 3 angle-bars 7 are bolted, forming ways 8, between which the saw-gate 9 is vertically slidable. The angle-bars are adjustable toward or from each other, as shown, to regulate the width of the ways and take up the wear of the reciprocating bars. The gate is

provided on each side near its ends with laterally-extending lugs 10, that are adapted to enter slots 11, provided near the ends of the bars 12, which are preferably of cast metal, 55 brass, bronze, or other suitable material and adapted to fit snugly in the ways and reciprocate therein. The lower ends of the bars are provided with locking-screws 13, that are adapted to enter the lugs at the lower end of 60 the gate and lock the bars in position thereon. The upper ends of the bars are hung on the lugs without being secured thereto. For the sake of economy in the metal the middle sections of the bars are preferably open and their 65 sides connected by bridges 14, against which the heads of screws 15 are adapted to abut, the opposite ends of said screws entering holes in the edges of the gate and provided with lock-nuts 16, by means of which the gate 70 can be easily and conveniently centered between the ways. The upper ends of the bars not being secured to the lugs on which they are hung permit the expansion of the bars due to their rapid reciprocation without in 75 any way affecting the lugs or straining the gate or the saws, and hence it will make no difference at what speed the gate be reciprocated the saws will never be put under any greater tension than they are subjected to 80 when secured in the gate. The bars are finished and have close-fitting joints with the ways and slide freely therein and for all purposes are a part of the gate itself except when they become heated through the rapid reciprocation of the gate, when they act independently thereof and relieve the saws of any possibility of undue tension being applied to 85 them. At its lower end the gate is provided with the usual coupling 17, by means of which 90 the gate is connected to the operating mechanism. (Not shown.)

I claim as my invention—

1. In a gang-saw, bars supported on the gate between it and the frame and adapted to reciprocate with the gate in the ways, said bars being secured at one end to the gate and supported thereon without being attached thereto at the opposite end, whereby expansion of the bars without affecting the gate or 95 the tension of the saws is permitted.
2. In a gang-saw, the combination, with a

- saw-gate provided with lugs or projections on its edges, of bars hung on said lugs and secured at one end only and ways wherein said bars are slideable.
5. 3. The combination, with a frame having ways, of a reciprocating gate provided on each edge with a plurality of laterally-extending lugs, bars having slots to receive said lugs and adapted to reciprocate in said ways and fastening devices for securing said bars at one end only to said lugs.
4. In a gang-saw guide, bars interposed between the saw-gate and frame and secured at one point to said gate and loosely supported thereon at another point, and adapted to reciprocate in the ways in said frame and to expand without affecting the gate or the tension of the saws.
5. The combination, with a suitable frame provided with vertical ways, of a reciprocating saw-gate, bars provided in said ways and each normally supported thereon at a plurality of points, and means for securing said bars to said gate at one point only.
25. 6. In a gang-saw, the combination, with a frame provided with suitable ways, of a reciprocating saw-gate, bars provided in said ways and normally supported on said gate at a plurality of points, means for securing each bar to said gate at one point only, and means for centering said gate between said bars.
7. The combination, with a suitable frame having vertical ways, of a saw-gate provided in its opposite edges near the ends with laterally-extending lugs, and bars adapted to reciprocate in said ways and each having slots to receive said lugs, said bars being loosely hung on the lugs at one end, and means for securing them to their respective lugs at the other end.
8. The combination, with a suitable frame having vertical ways, of a saw-gate provided in its opposite vertical edges near the top and bottom with laterally-extending lugs, elongated bars adapted to slide in said ways and each having slots near its ends to receive said lugs, said bars being loosely hung on said lugs at their upper ends, and set-screws for securing said bars to their lugs at their lower ends, substantially as described.

In witness whereof I have hereunto set my hand this 27th day of May, 1902.

EDWIN E. THOMAS.

In presence of—
RICHARD PAUL,
M. C. NOONAN.
